Patented Aug. 1, 1916.

Inventor.
Hermann H. Lott,
by Ralph Tauch
his Attorney.

UNITED STATES PATENT OFFICE.

HERMANN H. LOTT, OF ST. LOUIS, MISSOURI.

JEWELRY.

1,192,918.

Specification of Letters Patent. Patented Aug. 1, 1916.

Application filed December 17, 1915. Serial No. 67,417.

To all whom it may concern:

Be it known that I, HERMANN H. LOTT, a citizen of the United States, residing at the city of St. Louis, State of Missouri, have 5 invented certain new and useful Improvements in Jewelry, being a continuation of my application for Letters Patent for link for bracelets or the like, filed May 24, 1915, Serial No. 30,022, and also of my application 10 for Letters Patent for jewelry, filed October 14, 1915, Serial No. 55,910, as to all matter common to the several applications, of which the following is a specification, reference being had to the accompanying drawings, forming a part thereof.

This invention relates generally to jewelry and, more particularly, to certain new and useful improvements in jewelry of that class or kind known as bracelets or wrist- 20 ornaments.

The principal object of my present invention is to provide, as jewelry articles, so called links, especially adapted and designed for bracelets or the like, and separable connecting-members therefor, the connecting-members and links being detachably engageable and the links, through said connecting-members, being not only easily interchangeably lockingly attachable one to the other in 25 forming the completed or finished bracelet, but also readily detachable, when desired, one from another, and by means of which connecting-members either individual links or a plurality of connected links may be 30 conveniently threaded upon, and displayed attractively upon the wrist by, a ribbon or other flexible band.

With the above and other objects in view, my present invention resides in certain novel 40 features of form, construction, arrangement, and combination of parts, all as will herein-after be described and afterward pointed out in the claims.

In the accompanying drawing, which 45 shows my invention in preferred form, Figure 1 is a side elevational view of a bracelet formed of or comprising links and connecting-members embodying my invention; Figs. 2, 3, 4, and 6 are plan views of the 50 several complementing or coöperating parts forming, when assembled, the completed or finished link proper; Fig. 5 is a plan view of the link connecting-member or strap; Fig. 7 is an inverted plan view of the link 55 proper with the outer or back-plate thereof removed; Fig. 8 is a similar view, also illus-

trating a pair of connecting-members or straps in attached relation with the link; Fig. 9 is a longitudinal sectional view through one of the links, illustrating in 60 side elevation portions or fragments of additional links in attached relation therewith; Fig. 10 is a view partly in side elevation and partly in longitudinal section of one of the links, illustrating in connection with the 65 link a portion of one of the connecting-members and a link-disengaging tool in operative applied position prior to actual disengagement of the connecting-member from the link; Fig. 11 is a similar view of the 70 link, showing a connecting-member in side elevation removed therefrom; Fig. 12 is an inverted plan view of one of the links and a pair of connecting-members in connection with and threaded upon a displaying-ribbon or band; Fig. 13 is a fragmentary view of a connected pair of the links; and Fig. 14 is a perspective view of the tool preferably employed by me in disengaging or detaching the link and connecting-member or 80 strap.

Referring to the said drawing, in which like reference characters refer to like parts through the several views, A indicates one of the bracelet-links, which is preferably 85 approximately rectangular in shape and slightly curved or arched longitudinally. The link A comprises or includes a body-member, shell, or casing preferably of any suitable metal stamped or cupped to provide 90 an outer top portion or wall 1, upon which in the finished link may appear any suitable or desirable design, ornamentation, or the like, and laterally disposed or flanged side-portions or walls 2—2, and end-portions or 95 walls 3—3, both end walls 3 being cut-away, as at 4, for purposes soon to appear.

Fitting flatwise snugly within the body-member or shell of the link and upon the under or inner face of top wall 1 thereof, is 100 a plate 5 preferably of sheet metal. Provided in plate 5 adjacent its opposite ends and preferably integrally, as by punching or the like, is a pair of oppositely disposed connecting-member engaging-springs 6—6, 105 each of said springs obliquely facing toward the longitudinal center of the link and having its free end yieldingly presented outwardly away from said body-member or shell.

Fitting flatwise upon plate 5 within the confines of the shell or body-member of the 110

link, is a second plate 7 approximately H-shaped in plan view, as seen particularly in Fig. 4, plate 7 being cut-away at its opposite ends to provide a pair of oppositely-disposed approximately U-shaped guide-frames embracing and surrounding the springs 6 of plate 5, as seen particularly in Fig. 7. As seen especially in Figs. 7 and 8, the legs of said guide-frames are presented outwardly toward the cut-away portions or openings 4 in the end walls 3 of the shell of the link, the said guide-frames provided by plate 7 each having a width approximately the same as the width of said openings 4. Also snugly fitting flatwise within the confines of the shell of the link and upon and covering plate 7 with its said guide-frames, is a shell-closing plate or wall 8, the side and end walls 2 and 3 of the shell being crimped or inturned upon the outer face of wall or plate 8, as seen in Fig. 12, to rigidly retain the several plates 5, 7 and 8 within the body-member or shell of the link. In proper operative position relatively to springs 6 of plate 5, outer plate or wall 8 is provided, for purposes shortly appearing, with a pair of suitable perforations or apertures 9—9.

10 indicates the connecting-member for the links, this member or strap comprising a pair of approximately rectangular flat portions or parts 11—11 hingedly fastened together at one end, as at 12. Strap 10 is adapted to slidably fit snugly, but removably, at either of its said portions 11 within either of the said guide-frames of the link, each strap-portion 11 being cut away within its area to provide an enlarged opening or aperture 13 adapted, when such strap-portion is within the link, as shown in Fig. 8, to overlie a spring 6 of plate 5. To facilitate the removal or withdrawal of each strap-portion 11 from within the link, the inner edge of its aperture 13 is recessed, as at 14, thereby also providing corners or shoulders 15 projecting inwardly relatively to aperture 13.

In use or operation, links A being constructed as described, to attach a link A to a second link A, a part 11 of a connecting-member 10 is endwise slidably inserted through the opening 4 at one end of the first link A into the presented guide-frame thereof. In such movement, said strap-part 11 first rides upon, and thereby depresses, the particular spring 6 of such guide-frame; said spring 6 afterward, when said strap-portion 11 has been fully inserted within, and embraced by, said guide-frame, projects obliquely into the aperture 13 of said strap-portion 11 and engages with said corners or shoulders 15 of the strap-portion 11. Then the other or free strap-portion 11 of said connecting-member 10 is correspondingly or similarly engaged with the second link A, the two links A being thereby detachably

locked hingedly together. To detachably disconnect the links or a link A from a connecting-member 10, I preferably employ the tool B illustrated in Fig. 14. This tool B is provided at its forward end with a depending flange 16, and projecting outwardly from said flange at preferably the center thereof is a small stud or pin 17. This pin 17 of the tool B is adapted to be inserted through either aperture 9 of the outer or back-plate 8 of the link to depress the corresponding spring 6 out of engagement with the shoulders 15 to release the particular strap-portion 11. Tool B remaining in its described operative engagement with the link, the said strap-portion 11 cannot be at once entirely disconnected or detached from the link, due to the engagement of tool B at its pin 17 with said strap-portion; the connecting strap-portion 11, however, may now, due to said recess-continuation 14 of aperture 13 of the strap-portion, be moved outwardly relatively to the link a limited distance depending upon the depth of said recess 14. The connecting strap-portion 11 being so moved outwardly, the shoulders 15—15 thereof will ride upon the said spring 6 and thereby, on tool B being now removed from engagement with the link and also with said strap-portion, hold said spring 6 in depressed or unlocking position, whereupon, as will be evident, the connecting-strap portion may be entirely detachably disconnected or disengaged from the link. It will thus be seen that while a link A and a connecting-member 10 are readily and easily detachably connected, the same are, when in operative connection one with the other, firmly and securely locked together and that they cannot be detachably disconnected or separated except by positive operation on the part of the wearer or user. Any desired number of links A may thus be readily detachably connected by means of the connecting-members 10 to form a complete or finished bracelet of the required size, as illustrated in Fig. 1, the bracelet so formed being, due to the hinges 12 of the connecting-members 10, exceedingly flexible to meet all requirements. The connecting-member 10 is also useful in adapting either an individual link A or a plurality of connected links A to receive a displaying ribbon or band C, whereby such individual or connected links may be attractively displayed upon the wrist, the apertures 13 of the projecting strap-ports 11 of the two connecting-members 10 at the opposite end of such link, as illustrated in Fig. 12, or at the opposite or free ends of the several connected links, as will be well understood, providing passages through which the displaying ribbon or band may be easily and conveniently threaded.

While I have herein shown and described

my invention as a bracelet-link, for which use it is especially adapted and designed, it is to be understood that the same may equally well be applied to other jewelry articles or 5 the like, and that changes in the form, construction, arrangement, and combination of the several parts thereof may be made and substituted for those herein shown and described without departing from the nature 10 and principle of my invention as defined by the appended claims.

Having thus described my invention, what I claim and desire to secure by Letters Patent is;

15 1. In a jewelry article, a pair of links, each of said links including spaced apart top and back walls and side walls therebetween and each of said links having an opening thereinto at its end, and means for detachably fastening said links together, said means including a connecting-member having portions adapted to removably fit within each of said respective links.

20 2. In a jewelry article, a pair of links, each of said links including spaced apart top and back walls and side walls therebetween and each of said links having an opening thereinto at its end, and means for detachably fastening said links together, 25 said means including a connecting-member having portions adapted to removably fit within each of said respective links, each of said links being adapted for releasable engagement with said portions of the connecting-member.

30 3. In a jewelry article, a pair of links, each of said links including spaced apart top and back walls and side walls therebetween and each of said links having an opening thereinto at its end, and means for detachably fastening said links together, said means including a connecting member having apertured portions adapted to removably fit within each of said respective 35 links, and springs carried by said links adapted to project into the apertures of, and releasably engage with, said portions of the connecting-member when the same are within the links.

40 4. In a jewelry article, a pair of approximately rectangular links, each of said links including spaced apart top and back walls and side walls therebetween and each of said links having an opening thereinto at its end, and means for detachably fastening said links together, said means including a connecting-member having apertured approximately rectangular portions adapted to removably fit within each of said respective 45 links, and depressible springs carried by said links adapted to project into the apertures of, and releasably engage with, said portions of the connecting-member when the same are within the links, each of said 50 links being provided with an aperture in its

back wall to receive independent means adapted to engage with said springs to depress the same out of engagement with said portions of the connecting-member to permit withdrawal of the same from the links. 70

5. In a jewelry article, a pair of links, each of said links including a body-portion comprising top, side, and end-walls, a back wall fixed to said side and end walls and spaced from said top-wall, and a guide-frame within the body-portion intermediate said top and back walls, an end-wall of the body-portion being cut away to provide an opening into said guide-frame, and means for detachably fastening said links together, said means including a connecting member having apertured portions adapted to removably fit within the respective guide-frames of said links, and depressible springs within each of said links adapted to project 80 into the apertures of, and releasably engage with, the portions of said connecting-member when the same are within said guide-frames, each of said links being provided with an aperture in its back wall to receive 85 independent means to engage with said springs to depress the same out of engagement with said portions of the connecting-member to permit withdrawal of the same from the links. 90

6. In a jewelry article, a pair of links, each of said links including spaced apart top and back walls and side walls therebetween and each of said links having an opening thereinto at its end, and means for detachably fastening said links hinged together, said means including a connecting-member comprising a pair of oppositely disposed portions hinged together, said portions being adapted to removably fit within 100 said links.

7. In a jewelry article, a pair of approximately rectangular links, each of said links including spaced apart top and back walls and side walls therebetween and each of said links having an opening thereinto at its end, and means for detachably fastening said links hinged together, said means including a connecting-member comprising a pair of oppositely disposed approximately rectangular portions hinged together, said portions being adapted to removably fit within 110 said links.

8. In a jewelry article, a pair of approximately rectangular links, each of said links including spaced apart top and back walls and side and end walls therebetween, and a guide-frame within the link intermediate said top and back walls, an end wall of the link being cut away to provide an opening 120 into the guide-frame, and means for fastening said links hinged together, said means including a connecting-member comprising a pair of oppositely disposed approximately rectangular portions hinged together, said 125 links being provided with an aperture in its

portions being adapted to fit within said guide-frames, and springs within the links adapted to engage with the portions of said connecting-member when the same are within the links.

9. In a jewelry article a link comprising spaced apart top and back walls and side walls therebetween, said link having openings thereinto at its opposite ends, and a link 10 connecting-member comprising a pair of oppositely disposed portions, either of said portions being adapted to fit removably in the link at either of its ends.

10. In a jewelry article, a link comprising 15 spaced apart top and back walls and side walls therebetween, said link having openings thereinto at its opposite ends, and a link connecting-member comprising a pair of oppositely disposed portions hinged together, 20 either of said portions being adapted to fit removably in the link at either of its ends.

11. In a jewelry article, a link comprising spaced apart top and back walls and side walls therebetween, said link having openings thereinto at its opposite ends, and a link connecting-member comprising a pair of 25 oppositely disposed apertured portions hinged together, either of said portions being adapted to fit removably in the link at either 30 of its ends.

12. In a jewelry article, a link comprising spaced apart top and back walls and side and end walls therebetween and a pair of oppositely disposed guide-frames within 35 the link intermediate said top and back walls, the link being cut-away at its opposite end walls to provide openings into said guide-frames, a link connecting-member comprising a pair of oppositely disposed apertured 40 portions hinged together, either of said portions being adapted to fit removably in the

link at either of its said guide-frames, and springs within the link yieldingly projecting into said guide-frames, said springs being adapted, respectively, to engage with the 45 portion of the connecting member within the link to releasably fasten the same to the link.

13. In a jewelry article, a link comprising spaced apart top and back walls and side walls therebetween, said link having openings thereinto at its opposite ends, and connecting members fitting in the opposite ends of said link and having apertured portions projecting exteriorly thereof.

14. In a jewelry article, a link comprising 55 spaced apart top and back walls and side walls therebetween, and connecting-members fitting in the opposite ends of said link, each of said connecting-members having an apertured hinged portion projecting exteriorly of 60 the link.

15. In a jewelry article, a link comprising spaced apart top and back walls and side walls therebetween, and a connecting member having a hinge-portion fitting within 65 and engaged by said link and an apertured portion projecting exteriorly of the link.

16. In a jewelry article, a link comprising spaced apart top and back walls and side and end walls therebetween, and a guide-frame intermediate said top and back walls, an end wall of the link being cut away to provide an opening into said guide-frame, and a connecting-member having a portion fitting in said guide-frame and fastened to 75 the link and a second apertured portion projecting longitudinally exteriorly of the link.

In testimony whereof, I have signed my name to this specification.

HERMANN H. LOTT.
